UNITED STATES PATENT OFFICE.

KARL WILLIAM HAAK, OF TEXARKANA, ARKANSAS.

DESIGN FOR A BICYCLE-TIRE PROTECTOR.

SPECIFICATION forming part of Design No. 30,037, dated January 17, 1899.

Application filed November 17, 1898. Serial No. 696,692. Term of patent 7 years.

To all whom it may concern:

Be it known that I, KARL WILLIAM HAAK, a citizen of the United States, residing at Texarkana, in the county of Miller and State of Arkansas, have invented and produced a new and original Design for a Bicycle-Tire Protector; and I do declare the following to be a full, clear, and exact description of the same, reference being had to the accompanying drawings, forming a part thereof.

Figure 1 is a side elevation of my invention. Fig. 2 is a cross-section of the same.

As shown in the accompanying drawings,

the leading or material feature of my design consists of a complete half-tire 1, encircling 15 the entire bicycle-tire, which is substantially crescent-shaped in cross-section.

Having described my invention, what I claim as new, and desire to secure by Letters Patent, is—

The design for a bicycle-tire protector as herein shown and described.

KARL WILLIAM HAAK.
